UNITED STATES PATENT OFFICE.

NELLIE G. MASON, OF PHILADELPHIA, PENNSYLVANIA.

INSIGNIA STRUCTURE.

1,326,604.

Specification of Letters Patent. Patented Dec. 30, 1919.

Application filed October 18, 1918. Serial No. 258,693.

To all whom it may concern:

Be it known that I, NELLIE G. MASON, residing at Philadelphia, in the county of Philadelphia and State of Pennsylvania, 5 have invented certain new and useful Improvements in Insignia Structures, of which the following is a specification.

My invention relates to insignia structure and while it is adapted for utilization in 10 building up any insignia and is to be so construed, yet it is particularly applicable in the production of insignia used on the uniforms of officers of the U. S. Army and Navy and will be described as embodied in 15 well known insignia of this type.

Heretofore, in the production of insignia which contain a predominant portion or in other words a foundation element in the 20 form of a symbol indicating membership or service, such as the "anchor" insignia associated with the uniforms of officers of the U. S. Navy, it has been customary to produce such foundation element by sewing a 25 form pad on a suitable base and then covering the pad with a smooth metallic ribbon known as "lame". The application of this "lame" is accomplished by securing one end to the base and then folding the material back and forth over the pad, the folds being 30 progressively advanced in overlapping relation until the pad is completely covered, the ends of the folds being secured to the base as they occur. This process of construction, especially where the foundation element is 35 of irregular and unusual design, is exceedingly intricate and slow and its correct execution requires highly skilled labor with accompanying high cost of production.

It is therefore the purpose of my present 40 invention to eliminate the use of "lame" and its demand for highly skilled labor in the production of insignia foundation elements; to correspondingly reduce the cost of production; to facilitate such production; to 45 render it possible to employ unskilled labor without reducing the standard of the product; to improve the brilliancy, neatness and general appearance of the resulting insignia; to render the insignia more durable and 50 easy of renovation and repair, and to avoid to a large extent the use of materials difficult and costly to obtain.

I will describe my invention as applied to the production of the well known insignia 55 used upon the uniforms of officers of the U. S. Navy, but it will be understood that

the application of the invention is in no way limited to this design of insignia nor to its form and method of production, the drawing and description being merely illustrative of one method of carrying the invention into practice.

In describing my invention in detail reference will be had to the accompanying drawing wherein like characters of reference 60 denote corresponding parts in the several views, and in which—

Figure 1 is a view in elevation of U. S. naval insignia embodying my invention;

Fig. 2, a section on the line 2—2 of Fig. 1; 70

Fig. 3, a section on the line 3—3 of Fig. 1;

Fig. 4, a perspective view of the foundation element of the insignia; and

Fig. 5, a perspective view of the foundation element looking at the bottom thereof. 75

Referring to the drawings my improved insignia structure is shown as comprising a base formed of the cloth 10 and the backing 11, the latter being of any desired material, such as buckram, to afford the necessary stiffness and provide a suitable holding member for the stitching which secures the elements of the insignia in place. The foundation element of the insignia is indicated generally at A in the form of an anchor. I 80 construct this foundation element from polished metal by stamping and in such manner that when the same is applied it will be considerably raised with respect to the cloth 10 except at the points 12 and 13 on the shank where it is flattened and provided with openings 14 through which the securing stitching is passed in subsequently applying the embroidery elements to complete 85 the insignia. In this instance I utilize burlion as an embroidery element to form the stock 15 and the symbolized rope or cable 16, the former passing over the flattened portion 12 and the latter over the flattened portion 13 of the shank. This embroidery 90 element is secured to the base by stitching and certain of the stitches pass through the openings 14 so that the application of the embroidery element in turn secures the foundation element to the base. In addition 95 I provide the flukes of the anchor with opening 17 at their inner ends through which stitches pass in the application of an embroidery element 18 of jaseran and the application of this element is such that it serves 100 to secure the forward end of the anchor to the base and conceals the junction of the

110

base and foundation element thereby greatly enhancing the embellishment of the insignia. The holding shackle 19 of the anchor, in this instance, is also formed by utilizing jaseran 5 as an embroidery element.

While I have specified the use of certain embroidery elements in building up the insignia I desire to state that the carrying of my invention into practice is not limited to 10 the use of any one or any number of embroidery elements and that where I use the term "embroidery element" in the claims it is my intention to include within its scope any embroidery element or any combination 15 of embroidery elements that may be suitable for the work at hand and which will meet the conditions imposed by the product being produced.

Another important feature of my invention resides in the fact that I stamp the 20 foundation element from thin pliable metal having a highly polished and smooth exposed surface. As a result of the pliable nature of the foundation element the completed insignia can readily bend and thereby conform to curvature of the part of the 25 garment to which it may be applied. In this respect the structure meets the fundamental requirements which have heretofore 30 rendered the use of "lame" necessary. By using a highly polished metal in producing the foundation element I enhance the brilliancy of the resulting insignia and render it possible to restore such brilliancy at intervals by cleaning and polishing the exposed 35 smooth surface portions of the foundation element.

I claim:

1. An insignia structure comprising a 40 base, a relatively rigid embossed design pro-

ducing foundation element on the base, partially forming the design of the insignia, an embroidery element associated with the foundation element and overlying the same at predetermined points to complete the design of the insignia, and fastening means engaged through overlying portions of the embroidery element and through the foundation element to simultaneously secure said elements to the base. 45

2. An insignia structure comprising a base, a relatively rigid embossed design producing foundation element on the base provided with grooved depressions and partially forming the design of the insignia, 50 an embroidery element overlying the foundation element at predetermined points to complete the design of the insignia and crossing the embossing in said grooved depressions, and fastening means engaged 55 through overlying portions of the embroidery element and through the foundation element to simultaneously secure said elements to the base.

3. An insignia structure comprising a 60 base, a relatively rigid embossed design producing foundation element on the base provided with apertures and partially forming the design of the insignia, an embroidery element overlying the foundation element at 65 points above said apertures and complete the design of the insignia, and stitching fastening the embroidery element to the base and threaded through said apertures. 70

In testimony whereof, I affix my signature 75 in the presence of two witnesses.

NELLIE G. MASON.
